UNITED STATES PATENT OFFICE.

WILLIAM CHARLES PLANK, OF LAS FLORES, LOWER CALIFORNIA, MEXICO.

GAS-ENGINE IGNITER.

No. 898,779.

Specification of Letters Patent. Patented Sept. 15, 1908.

Application filed September 11, 1906. Serial No. 334,085.

To all whom it may concern:

Be it known that I, WILLIAM CHARLES PLANK, a citizen of the United States, and a resident of Las Flores, Lower California, Mexico, have invented a new and Improved Gas-Engine Igniter, of which the following is a full, clear, and exact description.

This invention relates to certain improvements in ignition devices for internal combustion engines, and more particularly to that type of ignition device in which a small portion of the explosive charge is compressed in the ignition cylinder to such a pressure that it spontaneously ignites and serves for igniting the main charge in the main engine cylinder.

The object of the invention is to provide certain improvements in the means for controlling the communication between the auxiliary cylinder and the main cylinder.

It is well known that an explosive mixture may be compressed to a point where the heat of compression is sufficient to cause the spontaneous ignition of the mixture, but it is practically impossible to utilize this in the main cylinder of an explosion engine, as the time of explosion cannot be properly controlled to prevent back firing. By reason of this danger from premature explosions other means than compression are ordinarily used for igniting the charge.

In order to safely and positively ignite the mixture at the proper moment and by means of compression, I employ an auxiliary cylinder in which a small portion of the explosive mixture is compressed to a much higher pressure than that to which the main charge is compressed, and the explosion which takes place within the auxiliary cylinder automatically opens a port and permits the incandescent gases from the auxiliary cylinder to pass to the main cylinder and ignite the main body of the explosive mixture therein. A small piston is preferably actuated by a cam or eccentric whose position may be advanced or retarded at will, making it possible to advance or retard the ignition of the main charge. As the explosion takes place within the auxiliary cylinder, the pressure therein instantly rises, and a second piston within this auxiliary cylinder is forced back against the action of a heavy spring to a point where an exhaust port is opened, and the flame shoots out in the explosive mixture, making the ignition thereof positive and certain. This flame is much superior for igniting pur-

poses than the comparatively smaller cooler electric spark of an induction coil, which often fails to ignite the mixture when it contains too small a percentage of the combustible gas, or the gas and air are imperfectly mixed.

At the instant of the explosion in the auxiliary or ignition cylinder, the exhaust port closing piston is suddenly forced back against the action of the spring, and as soon as the ignited gas escapes into the main cylinder, this piston is returned under the action of the spring and at a high rate of speed.

One object of my invention is to provide a construction by which both of these movements of the piston are cushioned and the pounding or jarring of the parts is entirely eliminated.

Other advantages of my improved igniter will be readily apparent from an inspection of the device, and among these may be mentioned the simplicity of the structure, the small number of parts employed, and the fact that practically no attention need be paid to the device, as it is almost impossible for it to get out of order or clogged up.

Reference is to be had to the accompanying drawings forming a part of this specification, in which similar characters of reference indicate corresponding parts in all the figures, in which

Figure 1 is a central longitudinal section through a gas engine provided with my improved igniter; Fig. 2 is a detail of the auxiliary cylinder showing the position occupied by the parts as the auxiliary cylinder is filled with the explosive mixture; Fig. 3 shows the position of the parts as the mixture is being compressed in the auxiliary cylinder; Fig. 4 shows the position of the parts at the instant of the explosion in the auxiliary cylinder; and Fig. 5 shows the position of the parts a short time after said explosion.

It will be evident that my improved igniting device may be employed either with two-cycle or four-cycle engines, as the principle would be the same in either case, but in the accompanying drawings I have illustrated it as applied to a four-cycle engine of a common type, having a main cylinder 1, main piston 2, inlet port 3, exhaust port 4, and a water jacket 5, the construction of all of which will be readily apparent to one familiar with the art.

Mounted in the side wall of the main cylinder, adjacent the outer end thereof, is a small

auxiliary cylinder 6, having an inlet port 7 and an exhaust port 8, both of which communicate with the compression space in the main cylinder. In order that the passages 5 leading to the inlet port 7 and exhaust port 8 may be as short as possible to prevent the radiation of heat, I preferably construct the working cylinder of an enlarged diameter adjacent the outer end, thus forming an annular recess into which these passages lead and into which if desired, the exhaust valve may open. Within this small auxiliary cylinder 6 are placed two pistons 9 and 10, one of which is normally held in a position to close 10 the exhaust port 8 by the action of a heavy coil spring, while the other piston is reciprocated by suitable mechanism connected to the main crank shaft of the engine and by which it intermittently opens the inlet port 15 to the auxiliary cylinder, and after said cylinder is filled, compresses the small charge therein toward the opposite spring-pressed cylinder.

The exhaust port closing piston 9 is 20 mounted on a piston rod 11, extending through a suitable bearing block 12 secured to the upper end of the main frame of the engine, and the space above the piston 9, into which it is forced at the time of the explosion 25 in the auxiliary cylinder, communicates with the outside atmosphere through a small port 13 which prevents the compression of air back of the piston, which would interfere with the free upward movement of said piston. 30 Within a recess in the block 12 is a heavy coil spring 14, mounted on the piston rod 11 and bearing against a hollow screw block 15 in the end of the bearing block 12 and against a collar 16 rigidly secured to the piston rod 35 11. The lower end of the recess in the block 12 is so arranged as to exactly fit the collar 16 and coöperate with the latter to form a cushion to prevent the too sudden return of the piston 9 after the explosion in the auxiliary cylinder.

The piston 10 is secured to a piston rod 17, extending through the wall of the engine casting and terminating in a roller 18 bearing on a cam 19 mounted on a short auxiliary shaft 40 20. The piston rod 17 carries a heavy coil spring 21 bearing against the frame and against a collar 22 on the piston rod, the spring being adapted to hold the roller 18 in contact with the cam 19 at all times. The 45 cam 19 is rigidly secured to its shaft 20, which latter is rotated by a gear wheel 23 mounted thereon and of twice the diameter of a cam wheel 24 with which it meshes, and which latter is mounted on the crank shaft of 50 the engine. Thus the cam 19 is rotated only one revolution for every two revolutions of the crank shaft, and the main piston 2 goes through its four cycles while the auxiliary cylinder is going through but two. In other 55 words, the main engine illustrated is a four-

cycle one but the igniting device is only two cycle.

In the operation of my improved igniter the exhaust port closing piston 9 is normally held in the position shown in Figs. 2, 3 and 5, 70 and closes the exhaust port 8 into the main cylinder. The small piston 10 is drawn down to the position shown in Fig. 2; this is to uncover the inlet port 7 to the auxiliary cylinder at the time the main cylinder is receiving its charge, so that the auxiliary cylinder may also become filled with the explosive mixture, as indicated in Fig. 2. After the main cylinder becomes filled with the explosive mixture and the main piston starts 80 on the compression stroke, compressing to a certain extent the gas in the auxiliary chamber, the piston 10 is forced upward by the cam to close the inlet port 7, as indicated in Fig. 3, and as the cam is so shaped that the 85 piston 10 rises more rapidly than does the piston 2, the gas within the auxiliary cylinder is compressed to a much higher pressure than is the main charge in the main cylinder. After the main piston 2 has passed the dead 90 center and is about to return, the piston 10 reaches nearly the limit of its upward stroke, and at this time the charge within the auxiliary cylinder has become compressed to a pressure and heated to a temperature at 95 which it spontaneously explodes, and as the piston 10 cannot be forced outward the pressure generated causes the upward movement of the piston 9 against the action of the heavy coil spring 14, to a point at which the exhaust 100 port 8 has opened, and the incandescent gases from the auxiliary cylinder rush outward through the exhaust port 8, as indicated in Fig. 4, and ignite the main charge 105 and cause the expansion thereof and the forcing outward of the power piston 2. Most of the exhaust gases of the auxiliary cylinder rush outward through the exhaust port 8, and this is facilitated by a slightly further upward movement of the piston 10. As 110 soon as the pressure in the auxiliary cylinder 6 has become reduced by the escape of the gases after the explosion, the piston 9 returns under the action of the spring 14 to the position shown in Fig. 5, the instantaneous 115 return being prevented by the cushion formed beneath the collar 16 on the piston rod of the piston 9. The pistons 9 and 10 remain in the relative positions shown in Fig. 5 during the remainder of the expansion stroke 120 of the main piston and during the scavenging stroke, the piston 10 not being withdrawn to open the inlet port 7 until during the suction stroke or during the end thereof, when the piston 10 is withdrawn to open the inlet port, 125 and a fresh supply of fuel rushes in, and may, if desired, be somewhat compressed therein upon the compression stroke of the main piston before the piston 10 can rise to compress the small charge to the ignition point and 130

cause a repetition of the operation above described. The time of the explosion within the auxiliary cylinder may be timed by changing the relative position of the cam 19 in respect to the crank shaft, such adjustment being produced in any suitable manner. In the engine shown, I provide the auxiliary shaft 20 with threads of considerable depth fitting threads in the gear wheel 23, and provide means whereby the position of the gear wheel on the shaft may be longitudinally adjusted, said means comprising a collar 25, engaging with forks on the end of a pivoted lever 26 mounted in the main frame of the engine and having a screw-threaded controller 27, passing through the opposite end. By rotating the controller 27 the gear wheel 23 may be shifted longitudinally of the shaft 20, and the compression stroke of the piston 10 retarded or advanced in respect to the compression stroke in the main cylinder, so that the igniting explosion may take place at any time desired. The pressure to which the small charge is compressed may be varied at will by adjusting the tension of the spring 14, such adjustment being easily accomplished by the rotation of the screw block 15.

Having thus described my invention, I claim as new and desire to secure by Letters Patent:

1. An internal combustion engine, comprising a main cylinder, an auxiliary cylinder communicating with the main cylinder by inlet and exhaust ports entering the main cylinder adjacent the outer end thereof, a piston within the auxiliary cylinder, serving to close the inlet port of said auxiliary cylinder, a second piston within said auxiliary cylinder and normally closing the exhaust port thereof, a piston rod carried by said sec-

ond piston, means for supporting and guiding said piston rod, said means having a cylindrical recess, a collar carried by said piston rod and adapted to coöperate with said recess to form a cushion upon the inward movement of the last-mentioned piston, and a spring in engagement with said collar and normally forcing the piston into its exhaust port closing position, the auxiliary cylinder being provided with an air exhaust port intermediate its ends and communicating with the outside atmosphere, whereby the movement of the exhaust port closing piston is cushioned when the latter approaches either of its two limiting positions.

2. An igniter for internal combustion engines, comprising an ignition cylinder having an exhaust port delivering to the engine cylinder, a piston within said ignition cylinder, means for reciprocating said piston to compress the charge in the ignition cylinder to the point of ignition, a second piston within said ignition cylinder and normally closing the exhaust port thereof, a piston rod carried by said second piston, a collar carried by said piston rod, and a spring in engagement with said collar, the wall of the auxiliary cylinder being provided with a passage communicating with the atmosphere, whereby the air may escape to permit outward movement of the second piston, and said wall being also provided with a recess adapted to receive the collar and cushion the inward movement of the piston.

In testimony whereof I have signed my name to this specification in the presence of two subscribing witnesses.
